Attorney.

UNITED STATES PATENT OFFICE.

CHARLES A. NEAL, OF SEATTLE, WASHINGTON.

PLUG FOR GASOLENE-TANKS.

1,187,769.

Specification of Letters Patent. Patented June 20, 1916.

Application filed June 15, 1914. Serial No. 845,304.

To all whom it may concern:

Be it known that I, CHARLES A. NEAL, a citizen of the United States, and resident of Seattle, King county, Washington, have 5 invented certain new and useful Improvements in Plugs for Gasolene-Tanks, of which the following is a specification.

My invention relates to plugs for gasolene tanks, and comprises certain novel 10 parts and combinations of parts which will will be hereinafter described and more particularly pointed out in the claims.

The object of my invention is to provide means whereby the air pressure in the tank 15 may be increased and retained, to thereby force the gas into the carbureter.

In the accompanying drawings I have shown my invention in its present preferred form, in two modifications which are essentially 20 the same in principle.

Figure 1 is a top plan view of the plug for the filling opening of the gasolene tank, showing my invention incorporated therein in its preferred form. Fig. 2 is a sectional view of the same along the line A—A of Fig. 1. Fig. 3 is a top plan view of a modified construction. Fig. 4 is a sectional view of the construction shown in Fig. 3, taken along the line B—B of Fig. 3. 25 Fig. 5 is a longitudinal sectional view on an enlarged scale, of the valve stem shown in Figs. 1 and 2. Fig. 6 is an end view of the same. Fig. 7 is a plan view of the valve handle used in Figs. 1 and 2.

30 My invention is intended particularly for use on automobiles, but may be used in any place where it is desired to increase and retain air pressure in a tank.

When going up a steep hill, if the supply 35 of gasolene in the tank is low, it often happens that the gasolene will refuse to flow from the tank to the carbureter, because of the fact that the level of gasolene in the tank is lower than the level in the carbureter. To overcome this, a special 40 pump is sometimes connected up with the tank so that the pressure of the air inside the tank may be increased, or the gasolene in the tank is kept under pressure at all 45 times. To keep the gasolene under pressure at all times is expensive and unnecessary, as there would be no occasion for the use of this pressure except at widely separated 50 intervals. On the other hand, the permanently attached pump, with its special con-

nections, is expensive in first cost and is, moreover, an expense which by my invention may be avoided.

By my invention I provide the plug or stopper for the filling opening of the gasolene tank, with an air inlet opening and a valve by which it may be closed and made airtight and provide this with means for attachment of the common tire pump, whereby, when necessary, air pressure may 60 be secured in the tank sufficient to force the gasolene to the carbureter irrespective of their relative levels.

In my preferred form, shown in Figs. 1 and 2, I provide the plug 1 with a boss 10, 70 which has an inclined bore 14 in which is seated a valve 2. The bore 14 is preferably at a slight angle, say 30° from the horizontal, as this reduces the height and does not infringe upon the space occupied 75 by the cushion which is usually placed over the tank. The boss 10 has a lateral projection 11, herein shown at right angles to the bore 14, which is threaded for the attachment of the ordinary hand pump which 80 forms a part of the standard equipment of automobiles. This projection 11 has an inlet port 12, which registers, when in operative position, with an inlet port 21 in the valve stem 2, which in turn communicates 85 with the central bore 22 in the valve stem, the whole forming an air passage from the inside of the gasolene tank to the outside atmosphere, or to the hand pump when this is connected. The stem of valve 2 has flattened portions 23 at its outer end, adapted to receive an operating arm 3, which is provided with a slot 31 of a size and shape to snugly fit the flattened portions 23. By this means valve stem 2 may be turned by the 95 handle 3. The outer extension of valve stem 2 beyond the flattened portions 23 is preferably threaded for the attachment of a nut or other securing means 25. The nut 25 and head 26 hold it securely in place in 100 the bore 14.

In another form of my invention, cap 1 has a lug 13 which is internally threaded for the reception of a small air valve of any of the types used on pneumatic tires. 105 This valve 2 is secured in place by nut 28 and lock nut 25, and is provided with cap 27 to protect the valve stem, the whole being of standard construction for such valves. In using this type of plug the air 110

in the tank must be kept under pressure at all times, or some other means provided for the inlet of air to the tank, or a separate plug of this type carried for insertion when 5 its functions are required.

- In the preferred form shown in Figs. 1 and 2, when the arm 3 is turned to one side the valve is open and remains so while the arm is in this position, thus providing free 10 passage of air to the interior of the tank, as in ordinary plugs. When it is desired to increase the pressure of the air in the tank, the hand pump may be quickly screwed into place on the projection 11, and 15 the pressure increased by pumping air in by hand. When the desired pressure is reached, the handle 3 is turned to the other side, which closes the air passage 22, and the pump may be detached.
- 20 It might be desired to incorporate an automatic air-retaining valve with the valve 2 as shown in Figs. 1 and 2, but I have not shown this for the reason that it is common to use air pumps which work in both directions.
- 25 Such pumps have incorporated in them an automatic air-retaining valve or its equivalent, and this will act to retain the air between strokes, until the required pressure has been obtained, particularly as this 30 pressure is very slight.

What I claim as my invention and desire to patent is:

1. As an article of manufacture, a shallow plug for the filling opening of gasoline tanks of automobiles having a valve-receiving bore extending therethrough at a considerable angle to the axis of the plug, and a lateral bore connecting the valve bore with the exterior, a valve rotatable in said first 35 named bore and having a port extending from its inner end to a position to register with said lateral bore.
2. As an article of manufacture, a shallow plug for the filling opening of gasoline tanks having a bore extending therethrough at a considerable angle to the axis of the plug, a valve rotatable in said bore and held 40 against axial reciprocation, the valve having a port communicating with its inner end and with its periphery back from said inner end, the plug having a bore extending laterally from the valve bore and adapted to connect said valve port with the exterior, and a valve controlling member secured to 45 the outer end of the valve.
3. As an article of manufacture, a plug for the filling opening of gasoline tanks having an axially bored boss with its axis placed at a considerable angle with the axis 50 of the plug, and also having a nipple extending laterally of said boss with a bore communicating with the bore in said boss, said nipple being threaded for the connection of a hose thereto, and a plug filling and 55 rotatable in the bore of said boss and hav-

ing an axial bore extending from its inner end and having a side opening registerable with the lateral nipple, said plug being held against reciprocation in said bore in the boss.

4. As an article of manufacture, a shallow 70 recessed plug provided with a low boss, a lateral bore extending therethrough and having its axis at a considerable angle to the axis of the plug, a seat surrounding the inner end of said bore, a nipple upon said 75 boss axially bored to communicate with said lateral bore, said nipple being adapted to receive a hose connection, a valve fitting in and rotatable to close said lateral bore, a head on the inner end of said valve engaging 80 said seat, the valve having a radial bore registerable with the bore in said nipple, and the valve being axially bored from its inner end to said radial bore, and a handle secured upon the outer end of said valve to 85 open or close the valve whereby the valve is held between said head and the handle to prevent reciprocation thereof.

5. As an article of manufacture, a shallow 90 plug for the filling opening of gasoline tanks having a valve-receiving bore extending therethrough at a considerable angle to the axis of the plug, a valve rotatable therein, a handle upon the outer end of the valve, the surface of the plug acting as a stop for 95 the handle in two extreme positions, one of said positions defining the open position of the valve, and the other position defining the closed position of the valve.

6. As an article of manufacture, a shallow 100 recessed plug provided with a low boss and having a bore extending therethrough at a considerable angle to the axis of the plug, a nipple secured upon said boss and having 105 an inlet opening communicating with said bore, a valve member in said bore and adapted to rotate therein, a head on the inner end of said valve member, a flattened portion upon the outer end of said valve member, a handle having a slot adapted to fit upon the 110 flattened portion of the valve member, the surface of the plug acting as a stop for the handle in two positions, means for securing said handle upon the valve, the valve having 115 an axial bore extending outward from its inner end, a radial bore communicating with said axial bore and registerable with said inlet opening in the nipple when the handle is in one extreme position, whereby said valve is opened, said valve being closed by 120 the rotation of the valve member until the handle is in the opposite extreme position.

7. A shallow plug for the filling opening 125 of automobile gasoline tanks, said plug being recessed upon its upper side and having a transversely extending boss upon this side containing a valve-receiving bore extending therethrough at a considerable angle to the axis of the plug, a valve rotatable in said bore having an inlet opening connecting 130

said bore with the exterior and a port connecting said inlet opening with the interior, a handle upon the outer end of said valve, said handle normally lying below the upper 5 surface of the plug and on opposite sides of the boss when said valve is in open and closed positions, respectively.

In testimony whereof I have hereunto affixed my signature this 5th day of June, 1914.

CHARLES A. NEAL.
